(Cl. D4—3)

To all whom it may concern:

Be it known that I, Albert Leebow, a citizen of the United States and a resident of East Rockaway, New York, have invented a new, original, and ornamental Design for Combined Razor Support and Magazine for Razor Blades or Similar Article, of which the following is a specification, reference being had to the accompanying drawing, forming a part thereof, in which

Figure 1 is a perspective view of a combined razor support and magazine for razor blades, or similar article, showing my new design;

I claim:

The ornamental design for a combined razor support and magazine for razor blades or similar article, as shown.

ALBERT LEEBOW.
